UNITED STATES PATENT OFFICE.

GEORGE W. McCUTCHEON, OF MARICOPA, CALIFORNIA.

PIPE-PLUG.

1,075,842.

Specification of Letters Patent. Patented Oct. 14, 1913.

Application filed November 18, 1912. Serial No. 732,145.

To all whom it may concern:

Be it known that I, GEORGE W. McCUTCHEON, a citizen of the United States, residing at Maricopa, in the county of Kern and State of California, have invented a new and useful Improvement in Pipe-Plugs, of which the following is a specification.

This invention relates to pipe plugs and particularly to pipe plugs which are adapted more particularly to plug the lower end of oil well pipes, and the principal object is to provide a plug which can be readily dropped to position and expanded when so placed.

It is also an object to provide suitable means to hold the members of the plug in their inexpanded position and to provide means for lowering the plug in this position.

It is a further object to provide locking means which securely lock the plug in position when the latter is expanded as desired.

In the drawings accompanying this specification and forming therewith the application for Letters Patent: Figure 1 is a perspective view of the plug in its assembled in-expansible form. Fig. 2 is a cross section on the line 2—2 of Fig. 1, viewed in the direction of the arrows. Fig. 3 is a view of the plug showing the latter expanded in the lower end of the well casing. Fig. 4 is a section on the line 4—4 of Fig. 3, looking in the direction of the arrows.

Heretofore in the operation of oil wells, operators have experienced considerable difficulty in properly closing the lower end of the casing to prevent undesirable lifting of material below this point when the oil is being pumped.

This invention overcomes the above difficulty in supplying a plug which is readily inserted in the casing and lowered to position where it can be expanded by means of a weighted tool to efficiently plug the lower end of the casing.

More specifically in the drawings like numbers indicate similar parts in the different views, 5 designating the casing of a well, in the lower end of which is shown the plug 6. This plug 6 is formed of two approximately semi-cylindrical sections. These two sections being provided with parallel diametrically located planes, which are inclined about an angle of 15° to the axial line of the cylindrical surface of the members. At oppositely disposed ends when assembled these parallel faces result in forming tangential surfaces 7 to the cylindrical surface at this

point so that the result of the cross section of the plug when expanded is approximately of elliptical form. The inclined surfaces are serrated transversely to the axial line 60 providing the saw-teeth 8 which are adapted to register and lock with one another, as clearly shown in the drawings, either in the assembled or the expanded position.

Axially disposed grooves are cut in the 65 inclined planes, these grooves 9 registering and acting as guide ways in the operation of expanding the plug. To secure the members of the plug in the inexpanded or assembled position, as spoken of previously, bores 70 10 are provided in the smaller end of each one of the members, which extend radially therethrough at right angles to the planes and register with smaller bores 11 in the opposite member which are threaded to receive 75 the screw 12, its head being preferably counter-sunk in the bore 10. These screws are sufficiently heavy to hold the two members together in the assembled position, as shown in Fig. 1, but not so as to resist the 80 shearing action of the adjacent edges of the groove formed by the bores in the metal of the members when pressure is applied to the upper end of the plug. With the plug in its assembled position, its cross section is such as 85 to slide readily in the casing, the upper end of the upper-most chamber being provided with the staple 13 to which suitable means may be attached, to lower or pull up in case it does not slide easily to the bottom of the 90 well. When the lower end reaches the end of the bore and the end of the casing, a weighted tool or plunger is dropped on the upper end until the screws are sheared and the upper members slide to the expanded 95 position as shown in Fig. 3, stretching the casing and making a tight closure.

The screws shear easily in such relation that a portion projects into the oppositely disposed groove way and assists in the guiding of the two members in their proper and efficient plugging of the end of the casing.

What I claim is:

1. A pipe plug, comprising a pair of approximately semi-cylindrical members having inclined diametric planes and provided with interlocking teeth thereon inclined, said planes also having longitudinally disposed and registering grooves, and means to secure said members in assembled form, whereby when force is applied to shear said securing means the projecting end of said means will

slide in the groove causing the shear to guide said members.

2. A pipe plug, comprising a pair of slide-
able members having inclined engaging
5 faces provided with interlocking teeth,
forming a cylindrical cross section when as-
sembled, the said members having oppo-
sitely disposed projecting ends, said engag-
ing faces also having longitudinally dis-
posed and registering grooves intersected by
10 a plurality of oppositely disposed threaded

bores, and bolts secured in said bores to hold
said members in assembled relation, said
bolts being sheared under pressure to one of
said members and forming guiding pins. 15

In witness that I claim the foregoing I
have hereunto subscribed my name this 8th
day of November, 1912.

GEORGE W. McCUTCHEON.
